MEANS FOR STIRRING DYEING BATHS

Arnold Wyssling, deceased, late of Basel, Switzerland, by Lina Wyssling-Meier, administratrix, Basel, Switzerland

Application June 19, 1950, Serial No. 168,877
In Switzerland May 6, 1949

1 Claim. (Cl. 68—183)

1
In all cases where it is desired to proceed with the dyeing of samples and the like on a large scale, it is found that the dyeing operation requires a somewhat considerable expenditure in time and labor, because it is necessary to move by hand the material to be dyed inside the bath in order to obtain a uniform coloration.

Now it has been found, in accordance with the invention, that it is possible to economize a considerable percentage of the labor involved by resorting to a simple apparatus for the stirring of the dyeing baths. Said apparatus introduces into the dyeing bath a continuous current of gas in order to stir the liquid and material to be dyed without it being any longer necessary to constantly inspect the operation. The execution of this method requires a particular arrangement including a pipe for admitting gas into the bath, said arrangement being associated preferably with means for holding the material to be dyed and preventing it from rising inside the dyeing bath. Furthermore, it is of advantage to secure a cover onto the vat, said cover being attached to the gas-admitting pipe in order to prevent any liquid from overflowing and more particularly any froth from running out of the vat.

The possibility thus achieved of dyeing perfectly even with dyestuffs that are difficult to distribute equally in a bath, forms an astonishing result for anyone skilled in the art, as such a result could not be reached heretofore, otherwise than through a continuous mechanical stirring of the material to be dyed.

My invention has for its object an apparatus for stirring or mixing dyeing baths according to which gas is fed into the dyeing bath through a tube leading to the vicinity of the bottom of said bath, the gas escaping then out of the end of the tube towards the free level of the bath in the shape of bubbles that provide an excellent stirring of the dyeing bath.

My invention has further for its object a device for stirring dyeing baths comprising a pipe for feeding gas down to the bottom of the bath and terminating at its lower end with a distributing system providing for a regular distribution of the gas.

I have described hereinafter with reference to accompanying drawings an embodiment of the invention selected by way of example.

In the single figure of said drawing, the dyeing vat 1 is drawn in dot-and-dash lines. Said vat containing the dyeing bath carries a dish-shaped cover 2 through which the gas-feeding

2
pipe 3 passes. Said pipe extending down to the bottom of the vat, is provided at its lower end with radial distributing pipes 3' provided each at its outer end with an opening 3'' directed downwardly and forming a nozzle. At an adjustable height inside the vat 1 the gas-feeding pipe is provided with a wheel-shaped member 4 that is intended for holding the material to be dyed, that is immersed in the bath, underneath it so that it may not rise inside the vat. This material-holding member 4 may as well be constituted by a perforated disc or a grating made of wire. The gas-feeding tube is also provided with a centering ring 5 secured to it and resting on the cover 2, said ring serving simultaneously as a suspension member for the pipe 3.

When it is desired to make use of the above described arrangement, the gas-feeding pipe is connected with a supply of compressed air and is introduced into the vat 1 containing the dyeing bath as well as the textile material to be dyed.

The air passing out of the nozzle 3'' rises inside the dyeing bath and forms bubbles therein whereby the dyeing liquid is set into motion. This ensures an excellent stirring of the bath and thereby a perfectly uniform dyeing of the textile material. In the case where a dyeing liquid is used that shows a tendency to frothing, the froth collects on the perforated cover 2 that is provided with a peripheral flange preventing any overflowing of liquid or loss of froth. The air feeding the pipe 3 may be cold or else it may be used after preheating in order to avoid any undesired cooling of the hot dyeing bath. Instead of air, it is possible to make use of nitrogen, which would be of particular interest in the case where the dyeing liquid is sensitive to the action of oxygen.

What is claimed is:

An arrangement for stirring dyeing baths contained in a vat comprising a dish-shaped cover for said vat having an upstanding peripheral flange thereon, said cover having perforations therein for the passage of froth out of the bath onto the cover and to be held thereon, an opening through said cover, a gas feeding pipe extending through said opening, a centering ring adjustably secured to said pipe and resting on said cover, said centering ring constituting a suspension member for said pipe, a plurality of radial horizontal pipes at the lower end of said gas feeding pipe having downwardly directed nozzle-shaped openings at the outer ends thereof adapted for the passage therethrough of gas, said radial pipe adapted for uniformly distributing gas inside the bath, and a vertically adjustable wheel-shaped member on

said gas feeding pipe between said cover and said radial pipes, said wheel-shaped member being adapted to prevent material to be dyed from rising above the level of said member.

LINA WYSSLING-MEIER,
Administratrix of the Estate of Arnold Wyss-
ling, Deceased.
